UNITED STATES PATENT OFFICE.

DAVID KARGER, OF MILWAUKEE, WISCONSIN.

KNITTED CAP.

1,395,230.

Specification of Letters Patent. Patented Oct. 25, 1921.

Application filed March 7, 1921. Serial No. 450,249.

To all whom it may concern:

Be it known that I, DAVID KARGER, a citizen of the United States, residing at Milwaukee, county of Milwaukee, and State of Wisconsin, have invented new and useful Improvements in Knitted Caps, of which the following is a specification.

My invention relates to improvements in knitted caps of that type in which the lower portion of the crown is wholly or partially encircled by a band which, when unfolded at the rear, will cover the back of the neck and ears of the wearer.

The primary object of my invention is to provide an improved cap of the above described type which will afford a better covering for the ears than those heretofore made; and which will allow a considerable range for variations in style with increased general serviceability as compared with the knitted caps heretofore used.

A further object of my invention is to provide a cap having the above stated advantages which can be cheaply and rapidly produced.

In the drawings:

Figure 1 is a side elevation of a cap embodying my invention.

Fig. 2 is a similar view showing a modified form of construction.

Fig. 3 is a similar view showing a second modification.

Like parts are identified by the same reference characters throughout the several views. My improved cap has a knitted crown 1 to which a band or section 2 of a band is secured along the lower margin of the crown. This band section 2 is held permanently in a raised position by a stitching, the stitching being preferably also used to connect buttons 3 with both the band section and the crown.

A cooperating or complementary band section 4 is similarly secured to the crown along its lower margin, but the stitching is of such character as to facilitate an adjustment of the band to a raised or to a dependent position as may be desired. The ordinary overhanging stitching is commonly used where the connected member is to be swung in folded or unfolded positions.

The band section 4 is adapted to encircle the rear portion of the head of the wearer and terminates above the ears. These end portions are extended or widened upwardly

or along the present longitudinal margin of the band section 4 to form ear muffs or flaps 7 where the bands are formed on a flat knitting machine provided with a rack lever. The flap 7 may be very expeditiously and cheaply made by racking the needles in such a manner as to form the triangular flaps illustrated in Figs. 1 and 2. In Fig. 1, the flaps 7 have their front margins 9 in close proximity to the end margins 10 of the band section 2 and the apices of the triangular members 7 are preferably provided with buttonholes and secured to the crown by buttons 12 stitched to the crown and adapted to hold the flaps 7 normally in the positions in which they are illustrated in Fig. 1. The upper margin 13 of the band section 4 is free from the cap or crown and therefore when the flaps 7 are unfastened from the buttons 12, the band section 4 may be swung downwardly thereby bringing the flaps 7 into an ear covering position.

In Fig. 2, the construction is the same as in Fig. 1 except that the margin 9 constituting the end margins of the section 4 and the lower front margin of the flap 7 is formed to overlap the end portions of the band section 2 and may, if desired, be buttoned to the buttons 14 which connect the ends of the band section 2 to the crown 15 of the cap. The flap 7' is somewhat wider than the flap 7 as shown in Fig. 1.

Referring to Fig. 3, it will be noted that the flaps 7" are elongated so that their apices overlap at the top of the cap, the crown being provided with a single button 16 to which both of the flaps may be connected. In Fig. 3, also, the flap 7" is illustrated as an independent flap stitched along its lower margin to the band and also to the crown 15 and adapted to be swung downwardly over the ears independently of the band. In this construction, the band may be formed in sections 2 and 4 but it is not material whether it is formed in sections or whether it is made continuous so far as the adjustment of the flaps 7" is concerned. It is also not material whether any buttons are used or not except that at the top of the crown either a button or equivalent fastening is desirable to hold the flaps 7" in a raised position.

In each of the forms disclosed, it is to be noted that the ear flaps or transverse extensions 7, 7', or 7" are preferably rack knitted in two directions as may be seen

from the drawing, thereby providing triangular transverse extensions without any raw or ragged edges. In the forms shown in Figs. 1 and 2, it is contemplated knitting 5 the band 4 in the usual manner until the triangular extensions are reached. At this point, the machine is caused to rack knit one half of the triangular extension. When this half has been rack knitted, the machine is 10 again set to rack knit, but in a different triangular direction, thereby forming the latter half of the triangular extension. By this means, the band is caused to merge into the triangular extensions and the triangular extensions are formed in a finished and attractive manner. It is also to be noted that by 15 rack knitting these extensions in the particular manner described, transverse strains that is to say, strains which are borne by the 20 ear flaps along their center lines do not cause unwanted or excessive stretching of the ear flaps.

I claim:

1. A knitted cap having a crown, and a 25 band secured to the rear and side portions of the crown and adapted to be swung upwardly or downwardly from the lower margin of the crown, the ends of the band being rack knitted to form transverse extensions

to provide ear muffs, and means carried by 30 said crown for temporarily holding said ear muffs in a raised position when said band is adjusted to an upwardly extending position.

2. A knitted cap having a crown, and a 35 band secured to the rear and side portions of the crown and adapted to be swung upwardly or downwardly from the lower margin of the crown, each end of the band being rack knitted in two directions to form transverse 40 triangular extensions to provide ear muffs, and fastening means carried by said crown for temporarily holding said ear muffs in a raised position when said band is adjusted to an upwardly extending position.

3. A knitted cap having a crown, and a 45 band secured to the rear and side portion of the crown and adapted to be swung upwardly or downwardly from the lower margin of the crown, each end of the band being rack knitted in two directions to form transverse 50 triangular extensions to provide ear muffs, each of said flaps having a buttonhole adjacent its apex and buttons carried by said crown for temporarily holding said ear muffs in a raised position when said band is ad- 55 justed to an upwardly extending position.

DAVID KARGER.
